UNITED STATES PATENT OFFICE.

GEORGE P. WIGGINTON, OF KALAMAZOO, MICHIGAN, ASSIGNOR TO KALAMAZOO LOOSE LEAF BINDER CO., OF KALAMAZOO, MICHIGAN.

TEMPORARY BINDER OR LOOSE-SHEET HOLDER.

1,218,734.

Specification of Letters Patent. Patented Mar. 13, 1917.

Application filed March 7, 1916. Serial No. 82,545.

To all whom it may concern:

Be it known that I, GEORGE P. WIGGINTON, a citizen of the United States, residing at Kalamazoo, county of Kalamazoo, State of Michigan, have invented certain new and useful Improvements in Temporary Binders or Loose-Sheet Holders, of which the following is a specification.

This invention relates to improvements in temporary binders or loose sheet holders.

My present improvements are an adaptation, and in some respects an improvement upon the structures shown in my application for Letters Patent filed March 19, 1915,

15 Ser. No. 15590.

The main objects of my invention are:

First, to provide an improved temporary binder or loose sheet holder which permits the rapid insertion or removal of sheets or 20 leaves and at the same time one in which the sheets are securely held when the binder is adjusted to retain the sheets, the sheets being freed when the binder is open to release the sheets.

25 Second, to provide a structure having these advantages which is well adapted for embodiment in comparatively small binders, thereby adapting the same for such use as binders for meter reading slips, order slips, 30 and the like.

Further objects, and objects relating to details and economies of construction and operation will definitely appear from the detailed description to follow.

35 I accomplish the objects of my invention by the devices and means described in the following specification.

A structure which is a preferred embodiment of my invention is illustrated in the 40 accompanying drawing, forming a part of this specification, in which:

Figure I is an inside view of a structure embodying the features of my invention with the covers extended, the sheet body 45 being shown sectioned in the plane of the binding strips and posts.

Fig. II is a detail section on a line corresponding to line 2-2 of Fig. I, with the binder closed.

50 Fig. III is a detail section on a line corresponding to line 3-3 of Fig. I, with the binder closed.

Fig. IV is an enlarged view partially in

section showing details of the post mechanism and the manner of mounting them on 55 the binder members.

Fig. V is a detail plan view of one of the sheets which the binder illustrated is designed to hold.

In the drawing similar reference characters refer to similar parts throughout the several views, and the sectional views are taken looking in the direction of the little arrows at the ends of the section lines.

Referring to the drawing, the covers 1 and 2 are provided with recesses or chambers 3 and 4 respectively. The recess 3 is adapted to receive the end of the flexible back piece 5, while the recess 4 is adapted to receive the adjusting mechanism of the binder. This 70 adjusting mechanism, designated generally by the numeral 6, and in the structure illustrated is substantially shown in Letters Patent No. 1010556, issued to me December 5, 1911. As the details of the adjusting mechanism form no part of my present invention they are not further described herein.

The binding strips 7 extend between the covers, being connected to the cover 1 at 8 and at their other ends to the adjusting 80 mechanism 6 carried by the cover 2. The clamping or binder members 9 are pivotally mounted on the covers, the binding strips being arranged to extend through these binder members. This pivotal arrangement 85 of the clamping members or similar arrangements are shown in my said application for Letters Patent. The back piece 5 telescopes into the chamber 3 of the cover 1. The inner wall of the cover is provided with a 90 slot 11 through which the strap 12 of the back strip projects so that the back strip may be adjusted after the binder is adjusted. The post members 13 are provided with threaded portions 14 adapted to be threaded 95 into the binder members 9, thereby removably securing the post members thereto.

The post members of the two binder members are arranged out of alignment as is best shown in Fig. I, so that they may overlap in 100 the leaf body, as shown.

The sheets 15 are provided with open notches 16 on their binding edges adapted to receive the binding strips 7 and with holes 17 adjacent their binding edges adapted to 105 receive the posts 13. When the binding

strips are extended sufficiently to permit the withdrawal of the binding posts carried by one member from the sheet body the binding strips may be swung out of the notches 16 5 entirely disengaging the same from the sheet body.

The post members are preferably provided with threaded sockets 18 at their outer ends so that one post member may be threaded 10 into another, thus providing an extension for such posts. When the covers are extended and the posts carried by one member withdrawn from the leaf body its post members may be disengaged and threaded into 15 those carried by the other body member, thus providing a support for all of the leaf body, or if desired, the entire leaf body may be lifted from the binder and the sheets manipulated as desired in the accounting system in which they are used.

If desired, when the binder is opened and the post members of one binder member mounted on those of the other the sheets may be offset in either direction as the holes 17 25 are spaced to permit this. This permits the arranging of the sheets in an aligned body or in offset groups, thus providing one of the features of the structure in my application for Letters Patent hereinbefore referred to.

I have illustrated and described my improvements as I have embodied the same in binders of moderate size. My improvements are, however, well adapted for use in binders designed for various purposes. I have not 30 attempted to illustrate or describe certain modifications or adaptations which might be desirable as I believe the disclosure made will enable those skilled in the art to which my invention relates to embody or adapt the 35 same as may be desired.

Having thus described my invention, what I claim as new and desire to secure by Letters Patent is:

1. In a temporary binder, the combination 45 with sheets provided with open notches in their binding edges and with a plurality of holes adapted to receive binding posts, of covers, clamping members pivotally connected to said covers, binding strips extending between said covers and adapted to engage said notches of said sheets, said binding strips being arranged through said clamping members, and post members having threaded engagement with said clamping members permitting their removal, the post members carried by one clamping member being out of alinement with those carried by the other and positioned to engage different holes in said sheets so that the post 50 55 members carried by one clamping member may overlap in the leaf body with those carried by the other, said post members having threaded sockets in their outer ends into which another post member may be threaded.

2. In a temporary binder, the combina-

tion with sheets provided with open notches in their binding edges and with a plurality of holes adapted to receive binding posts, of covers, clamping members pivotally connected to said covers, binding strips extending between said covers and adapted to engage said notches of said sheets, said binding strips being arranged through said clamping members, and post members carried by said clamping members, the post members carried by one clamping member being out of alinement with those carried by the other and positioned to engage different holes in said sheets so that the post members carried by one clamping member may overlap in the leaf body with those carried by the other.

3. In a temporary binder, the combination with sheets provided with open notches in their binding edges and with a plurality of holes adapted to receive binding posts, of binder members, binding members extending between said binder members and adapted to engage said notches of said sheets, and post members having threaded engagement with said binder members permitting their removal, the post members carried by one binder member being out of alinement with those carried by the other and positioned to engage different holes in said sheets so that the post members carried by one clamping member may overlap in the leaf body with those carried by the other, said post members having threaded sockets in their outer ends into which another post member may be threaded.

4. In a temporary binder, the combination with sheets provided with open notches in their binding edges and with a plurality of holes adapted to receive binding posts, of binder members, binding members extending between said binder members and adapted to engage said notches of said sheets, and post members carried by said binder members, the post members carried by one binder member being out of alinement with those carried by the other and positioned to engage different holes in said sheets so that the post members carried by one clamping member may overlap in the leaf body with those carried by the other.

5. In a temporary binder, the combination with sheets provided with open notches in their binding edges and with a plurality of holes adapted to receive binding posts, of binder members, a binding member extending between said binder members and adapted to engage said notches of said sheets, and post members removably mounted on said binder members, the post member carried by one binder member being out of alinement with that carried by the other and positioned to engage different holes in said sheets so that the post members may overlap in the leaf body, one of said post

members being adapted to be mounted on the other to provide an extension therefor.

6. In a temporary binder, the combination with sheets provided with open notches in their binding edges and with a plurality of holes adapted to receive binding posts, of binder members, a binding member extending between said binder members and adapted to engage said notches of said sheets, and post members carried by said binder members, the post member carried by one binder member being out of alinement with that carried by the other and positioned to engage different holes in said sheets so that the post members may overlap in the leaf body.

7. In a temporary binder, the combination with sheets having notches open at their binding edge and holes adjacent their binding edge, of binder members, binding members extending between said binder members and adapted to engage said notches of said sheets, said binding members being adapted to be swung out of engagement with the leaf body when the binding members are extended, and post members carried by said binder members and adapted to engage said holes in said sheets, the post member carried by one binder member being out of alinement with that carried by the other, one of said post members being removable from its binder member and adapted to be mounted on the other to provide an extension therefor.

8. In a temporary binder, the combination with sheets having notches open at their binding edge and holes adjacent their binding edge, of binder members, binding members extending between said binder members and adapted to engage said notches of said sheets, said binding members being adapted to be swung out of engagement with the leaf body when the binding members are extended, and post members carried by said binder members and adapted to engage said holes in said sheets, the post member carried by one binder member being out of alinement with that carried by the other.

9. In a temporary binder, the combination with sheets having notches open at their binding edge and holes adjacent their binding edge, of binder members, binding members extending between said binder members and adapted to engage said notches of said sheets, and post members carried by said binder members and adapted to engage said holes in said sheets, the post member carried by one binder member being out of alinement with that carried by the other, one of said post members being removable from its binder member and adapted to be mounted on the other to provide an extension therefor.

10. In a temporary binder, the combination with sheets having notches open at their

binding edge and holes adjacent their binding edge, of binder members, binding members extending between said binder members and adapted to engage said notches of said sheets, and post members carried by 70 said binder members and adapted to engage said holes in said sheets, the post member carried by one binder member being out of alinement with that carried by the other.

11. In a temporary binder, the combination of covers, clamping members pivotally connected to said covers, binding strips extending between said clamping members, and post members having threaded engagement with said clamping members permitting their removal, the post members carried by one clamping member being out of alinement with those carried by the other, said post members having threaded sockets in 80 their outer ends into which another post member may be threaded.

12. In a temporary binder, the combination of covers, clamping members pivotally connected to said covers, binding strips extending between said clamping members, 90 and post members having threaded engagement with said clamping members permitting their removal, the post members carried by one clamping member being out of alinement with those carried by the other.

13. In a temporary binder, the combination of binder members, a binding member extending between said binder members, and post members having threaded engagement with said binder members permitting their removal, the post member carried by one binder member being out of alinement with that carried by the other, said post members having threaded sockets in 100 their outer ends into which another post member may be 105 threaded.

14. In a temporary binder, the combination with sheets provided with open notches in their binding edges and a plurality of holes adapted to receive binding posts, of 110 binder members, an adjustable binding member extending between said binder members and adapted to engage said notches of said sheets and to be swung out of engagement with the leaf body when the binding member is extended, and post members carried by said binder members to coact with said holes in said sheets.

15. In a temporary binder, the combination of binder members, binding members 120 extending between said binder members, and post members carried by said binder members, the post member carried by one binder member being out of alinement with that carried by the other, one of said post members being removable from its binder member and adapted to be mounted on the other to provide an extension therefor.

16. In a temporary binder, the combination of binder members, binding members 130

extending between said binder members, and my hand and seal in the presence of two
post members carried by said binder members, one of said post members being remov-
ers, one of said post members being remov-
able from its binder member and adapted to
be mounted on the other to provide an ex-
tension therefor.

In witness whereof, I have hereunto set

my hand and seal in the presence of two
witnesses.
